(57) **CLAIM**

The ornamental design for an electrical connector, as shown and described.

DESCRIPTION

FIG. 1 is a front and top perspective view of an electrical connector showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is an enlarged view of area 8 indicated in FIG. 1;

FIG. 9 is an enlarged view of area 9 indicated in FIG. 2;

FIG. 10 is an enlarged view of area 10 indicated in FIG. 3;

FIG. 11 is an enlarged view of area 11 indicated in FIG. 6;

FIG. 12 is an enlarged view of area 12 indicated in FIG. 7;

FIG. 13 is an enlarged cross-sectional view taken along line 13-13 in FIG. 9;

FIG. 14 is an enlarged cross-sectional view taken along line 14-14 in FIG. 11;

FIG. 15 is an enlarged cross-sectional view taken along line 15-15 in FIG. 11; and,

FIG. 16 is an enlarged cross-sectional view taken along line 16-16 in FIG. 11.

The evenly spaced broken lines are provided to show portions of the electrical connector that are not being claimed, and thus form no part of the claimed design. The single dot-dash broken lines define the boundary of the claimed design and form no part of the claimed design. The double dot-dash broken lines illustrate the boundary of an enlarged area of the design.
